UNITED STATES PATENT OFFICE.

ALBERT HAMILTON EMERY, OF STAMFORD, CONNECTICUT.

BUILT-UP GUN.

1,244,719.

Specification of Letters Patent. Patented Oct. 30, 1917.

Application filed August 31, 1916. Serial No. 117,937.

To all whom it may concern:

Be it known that I, ALBERT HAMILTON EMERY, a citizen of the United States, residing at Stamford, in the county of Fairfield and State of Connecticut, have invented a certain new and useful Built-Up Gun, of which the following is a specification.

Many modern guns are of such large transverse dimension that they are built up 10 of several concentric pieces in order to admit of proper forging and tempering of the metal of which they are composed, and where the whole gun is so long as to render difficult the production and tempering of 15 forgings the full length of the gun, and make it extremely inconvenient to caliber and rifle the bore as a single piece, it has been proposed to make the gun in more than one longitudinal section.

20 Guns built up of a plurality of concentric sections are usually fully assembled, with the exception of the breech apparatus, before they are finally bored and rifled, great care being required to give to the bore the same diameter throughout its length, except 25 for a short distance near the shot seat where the bore is often made tapering for a distance equal to one or more diameters of the bore.

30 In making large guns according to the present invention, the body and chase of the gun are produced as two separate members, one comprising the main body of the gun, together with the rear part of the chase 35 which I shall hereinafter call the body member, and the other member comprising the remainder of the chase, and hereinafter called the muzzle member. Either of these two main members may be constructed from 40 a single piece of metal, but I prefer to make each of said members of several pieces, permanently assembled together by shrinking outer parts upon inner parts, or by permanently expanding inner parts outward 45 against parts which surround them, as I have described in other patents. The two main members of the gun may be bored and rifled after they are assembled together, but to do this, the lathe and rifling machine required would be very long and massive.

50 Consequently, I prefer to bore and rifle these two main members before they are assembled together. A good way to assemble the muzzle member with the body member is to

have the body member cold and the muzzle member heated sufficiently to allow the latter to be passed over the former, the distance which it is desired to have them overlap.

A gun constructed in accordance with the present invention is illustrated in the accompanying drawings, the details of construction being suitable for a 50-caliber gun. In said drawings—

Figure 1 is a plan of the complete gun;

Fig. 2 is a plan partly in axial section, 65 showing, on an enlarged scale, the portion of the gun extending from the breech end forward to about the line J—J of Fig. 1;

Fig. 3 is a view similar to Fig. 2, showing, 70 on the same enlarged scale, the portion of the gun extending from the muzzle end rearward to about the line J—J of Fig. 1; and

Fig. 4 is a detail view showing, in axial section upon a still larger scale, the portion 75 of the gun extending both forward and rearward from the line J—J of Fig. 1 and including the parts immediately concerned in making the joint between the body member and the muzzle member, which joint, in the present instance, is about two and one-half 80 calibers long.

In each of the figures, B represents the body member and M the muzzle member, while parts entering into the construction of these main members are given the same 85 letters distinguished by small letters as hereinafter indicated.

As already stated, the members B and M might be made each of a single piece of metal properly forged, tempered and 90 dressed, but in the gun selected for illustration, they are built up of a plurality of concentric parts. When thus built up, the front end B^a of the jacket, where it surrounds the inner part B^a, is preferably threaded, as 95 shown more clearly in Fig. 4, to avoid any danger of relative slipping between these parts at time of firing; and similarly the muzzle member M preferably has its parts M^b and M^c screwed together, as also shown 100 more clearly in Fig. 4.

The body member B and muzzle member M are assembled together by overlapping their meeting ends for a suitable distance, such for instance as the distance between the 105 line J—J where their jackets abut and the line K—K (Fig. 4) where their bore tubes abut. In a gun having the proportions sub-

stantially as shown in the embodiment of the invention selected for illustration, this distance will be about two and one-half calibers, and these abutting parts of the respective members are also stepped to produce offsets in their abutting faces. Moreover, where the part B^a of the body member is overlapped by the part M^a of the muzzle member, their overlapped faces are threaded together.

In fitting these two parts of the gun for assembling, great care must be used to see that the distances between the normal faces of the body member at $J-J$ and $K-K$ are greater than the corresponding distances between these normal faces on the muzzle member so that when assembled and shrunk together there will be a heavy strain of longitudinal tension on the overlapping muzzle 20 part and of longitudinal compression on the overlapped body part, and all the intervening normal adjoining faces should not touch each other when assembled.

In fitting the threads of the rear part M^a of the muzzle member and the forward part B^a of the body member, the fittings should be such that when the members are assembled and these parts have been brought to a common temperature, the faces B^x and M^x will be pressed very tightly together and likewise the faces T^x , T^x , of their threads, but there will be no pressure on the other faces of these threads. To accomplish this, the part M^a will be shrunk on the part B^a , 35 and the inner and outer diameters, respectively, of these parts will be so determined and the threads are so formed, that when the parts are in their proper places, shrinking of the part M^a upon the part B^a will 40 develop heavy pressure between the abutting faces B^x and M^x . This condition must be established in order to make this joint have the desired transverse stiffness.

In making the threads between the parts M^a and B^a , they should be so proportioned that the thread faces alternating with the bearing faces T^x will not touch each other.

If the body member and muzzle member of the gun are bored and rifled before assembling them together, the part M^b will be expanded so that it will have about the same diameter and strain of tension while this work is being done, as it will have in the assembled gun. Should it be bored without this temporary expansion, the bore of the muzzle member at M^y will be too large. Similarly, when boring the body part B^b , this part will be compressed tangentially while the work is being carried on, as otherwise the bore would be too small after assembling the part with the part M^b of the muzzle member, because the seizing pressure of the part M^b , if as great as it should be, will considerably reduce the diameter of 35 the bore in the part B^b .

A good way to reduce the part B^b , when boring, is to shrink a band upon it that has a seizing capacity sufficient to reduce the outer diameter of the part B^b the same as it will be reduced by assembling with the muzzle part M^b .

The part B^c which projects into the part M^c should have its outer diameter and length larger than corresponding dimensions of the seat provided in part M^c to receive it, so that when the body member and muzzle member are assembled, there will be large tangential and longitudinal strains of compression on the part B^c .

Grooves g are provided between the longitudinally overlapping faces of the parts M^c and B^c to render the joint gas-tight and prevent leakage at M^y . These grooves may be either in the exterior of part B^c or the interior of part M^c .

In fitting the parts M^b and B^b , the inner diameter of part M^b must be smaller than the outer diameter of part B^b , to the extent that when these parts are assembled together, part M^b will have the desired strain of tension and part B^b the desired strain of compression necessary to enable them to stand the strain of firing. The relative length of these parts is such as to give a large strain of longitudinal tension on the part M^b and of longitudinal compression on the part B^b . When thus properly proportioned, the friction between these parts when assembled will keep them from slipping one upon the other, at time of firing.

If the final boring and rifling of the two main members of the gun is done before assembling them together, care must be exercised to see that when they are assembled together, the rifling grooves of one exactly match those of the other.

When, in the foregoing specification or in the subjoined claims, the term "body member" or the term "muzzle member" is used, it is to be understood in each instance, unless specifically qualified, as meaning the particular member indicated, whether made of one piece of metal or built up of two or more pieces of metal firmly assembled together.

I claim:—

1. A gun formed of two main members, namely a body member, consisting of the body and a portion of the chase of the gun, and a muzzle member, said members being assembled together by overlapping the rear of the muzzle member upon the forward end of the body member through a very considerable portion of the longitudinal dimension of the gun, the inner diameter of the overlapping part of the muzzle member before assembling being less than the outer diameter of the overlapped part of the body member, so that after the rear end of the muzzle part has been shrunk on the front

end of the body part, the friction of the pressure between these overlapping parts will hold them firmly together.

2. A gun formed of two main members, namely a body member which constitutes the body and a portion of the chase of the gun, and a muzzle member; said members being assembled together by overlapping the rear end of the muzzle member upon the forward end of the body member through a considerable portion of the longitudinal dimension of the gun; each member being formed in its overlapped portion with a plurality of diameters; the interior diameters of the overlapping parts of the muzzle member before assembling being less than the exterior diameters of corresponding parts of the overlapped body part, and a large tangential strain of tension in the overlapping muzzle part, and a large strain of compression in the overlapped body part being thereby produced.

3. A gun formed of two main members, namely a body member which constitutes the body and a portion of the chase of the gun, and a muzzle member; said members being assembled together by overlapping the rear end of the muzzle member upon the forward end of the body member through a portion of the longitudinal dimension of the gun equal at least to a full caliber of the gun; each member being formed in its overlapped portion with a plurality of diameters; the interior diameters of the overlapping parts of the muzzle member before assembling being less than the exterior diameters of corresponding parts of the overlapped body part, and a large tangential strain of tension in the overlapping muzzle part and a large strain of compression in the overlapped body part being thereby produced.

4. A gun formed of two main members, namely a body member and a muzzle member assembled together by overlapping the meeting ends of said members; the inner diameter of the outer overlapping part before assembling being less than the outer diameter of the inner part overlapped, and said overlapping parts seizing tightly one upon the other; the rear portion of the overlapping part of the muzzle member being threaded onto the corresponding portion of the body member.

5. A gun formed of two main members, namely a body member which constitutes the body and a portion of the chase of the gun, and a muzzle member; said members being assembled together by overlapping the rear end of the muzzle member upon the forward end of the body member through a considerable portion of the longitudinal dimension of the gun; each member being formed in its overlapped portion with a plurality of diameters; the interior diam-

eters of the overlapping parts of the muzzle member before assembling being less than the exterior diameters of corresponding parts of the overlapped body part, and a large tangential strain of tension in the overlapping muzzle part and a large strain of compression in the overlapped body part being thereby produced; the rear portion of the overlapping part of the muzzle member being screwed onto the body member.

6. A gun formed of two main members, namely a body member and a muzzle member assembled together by overlapping the meeting ends of said members; the inner diameter of the outer overlapping part before assembling being less than the outer diameter of the inner part overlapped, and said overlapping parts seizing tightly one upon the other; the front end of the overlapped portions having small grooves between them which prevent passage of gas through the joint at the time of firing.

7. A gun formed of two main members, namely a body member and a muzzle member assembled together by overlapping the meeting ends of said members; the inner diameter of the outer overlapping part being less before assembling than the outer diameter of the inner part overlapped, and said overlapping parts seizing tightly one upon the other; the portion of the body member which enters the muzzle member being sufficiently longer than the recess that receives it, to leave the inner abutting faces pressed firmly together and make a gas-tight joint.

8. A gun formed of two main members, namely a body member and a muzzle member assembled together by overlapping the meeting ends of said members; the inner diameter of the outer overlapping part before assembling being less than the outer diameter of the inner part overlapped, and said overlapping parts seizing tightly one upon the other; the portion of the body member which enters the muzzle member being sufficiently longer than the recess that receives it, to leave the inner abutting faces pressed firmly together and make a gas-tight joint, when the members have been screwed and shrunk together to develop the seizing and sealing pressures.

9. A gun formed of two main members, namely a body member and a muzzle member assembled together by overlapping the meeting ends of the said members a considerable distance and bringing their normal faces firmly in longitudinal abutment by screwing them together; the relative diameters of said parts being such that they seize tightly one upon the other when assembled; the rear portion of the overlapping parts being threaded one upon the other; the threads having their bearing faces inclined in a direction to force the abutting faces of the parts firmly together; and thread

faces alternating with said bearing inclined faces, that remain out of contact.

10. A gun formed of two main members, namely a body member and a muzzle member assembled together by overlapping the meeting ends of the said members, the inner diameter of the outer overlapping part before assembling being less than the outer diameter of the inner part overlapped, 10 causing these parts to seize each other tightly when assembled and shrunk together, the front portion of the body member being made longer than the recess provided for it in the muzzle member, making 15 a gas-tight joint between their normal meeting faces after they are assembled, the rear part of the overlapping muzzle being threaded and of such length that when heated and screwed on to the body part the rear 20 normal face of the muzzle part will strike the corresponding face on the body part of the gun at the same time the normal face on the front end of the body part strikes the abutting face provided for it in the muzzle 25 part and the threads on the inner face of the rear end of the muzzle part have been so formed and positioned that when the muzzle part is heated and screwed on to the body part until its rear face strikes the body 30 part the decreasing diameter of the muzzle part, as it cools, will cause the inclined bearing faces of the threads to force the rear face of the muzzle part very firmly against the abutting face of the body to 35 give great transverse stiffness to the gun at this point.

11. A gun formed of two main members, namely a body member and a muzzle member assembled together by overlapping the 40 meeting ends of the members and bringing their end faces in abutment; each of the overlapping parts of the respective members having a plurality of end faces with intervening overlapping cylindrical faces 45 extending for a considerable portion of the longitudinal dimension of the gun, and the members being screwed together at the end of the outer overlapping part by screw threads which in assembling draw the members 50 firmly together longitudinally and leave the outer overlapping part under longitudinal strains of tension and the inner overlapped part under longitudinal strains of compression.

55. 12. A gun formed of two main members, namely a body member and a muzzle member assembled together by overlapping the meeting ends of said members; each member having its overlapping part constructed 60 with a plurality of diameters with shoulders providing longitudinal abutting faces at the adjoining ends of the members and offsets between the parts of different diameter; the overlapped parts being of such relative diameters that they seize very firmly one upon

the other when assembled and shrunk together, and the inner part of the body being provided with a sealing part projecting into a seat provided in the muzzle part to receive said sealing projection.

13. A gun formed of two main members, namely a body member and a muzzle member assembled together by overlapping the meeting ends of said members; each member having its overlapping part constructed 75 with a plurality of diameters with shoulders providing longitudinal abutting faces forming offsets between the cylindrical parts of different diameters; the overlapped parts being of such relative diameters that they 80 seize firmly one upon the other when assembled, and the innermost parts being provided adjacent to their longitudinal abutment with a sealing projection on one part and a seat on the other part to receive said 85 sealing projection; one of the circumferential faces of said sealing projection and seat being formed with intervening grooves to increase the sealing effect.

14. A gun formed of two main members, 90 namely a body member and a muzzle member assembled together by overlapping the rear end of the muzzle member upon the forward end of the body member; the overlapping parts of the respective members 95 being each constructed with a plurality of diameters and the relative diameters of the overlapping parts being such that the outer member seizes firmly upon the inner member when they are assembled; said members 100 embodying in their structure, outer jackets in addition to their inner parts; each jacket forming with the part within it, a radial offset providing a face for longitudinal abutment when the two main members 105 are assembled together and being threaded to the part within it to prevent longitudinal slipping under the abutting action.

15. A gun formed of two main members, 110 namely a body member and a muzzle member assembled together by overlapping the rear end of the muzzle member upon the forward end of the body member; the overlapping parts of the respective members 115 being each constructed with a plurality of diameters and the relative diameters of the overlapping parts being such that the outer member seizes firmly upon the inner member when they are assembled; said members 120 embodying in their structure, outer jackets in addition to their inner parts; each jacket forming with the part within it, a radial offset providing a face for longitudinal abutment when the two main members are 125 assembled together and being threaded to the part within it to prevent longitudinal slipping under the abutting action; threads being provided between the body member and the rear end of the jacket of the muzzle 130

member which draw the two main members longitudinally together in assembling.

16. A gun formed of two main members, namely a body member and a muzzle member assembled together by overlapping the rear end of the muzzle member upon the forward end of the body member; the overlapping parts of the respective members being each constructed with a plurality of diameters and the relative diameters of the overlapping parts being such that the outer member seizes firmly upon the inner member when they are assembled; said members embodying in their structure, outer jackets in addition to their inner parts; each jacket forming with the part within it, a radial offset providing a face for longitudinal abutment when the two main members are assembled together and being threaded to the part within it to prevent longitudinal slipping under the abutting action; threads being provided between the body member and the rear end of the jacket of the muzzle member which draw the two main members longitudinally together in assembling; the longitudinal dimensions of the overlapped parts of the body member lying between its abutting faces being greater than the corresponding dimensions of the overlapping parts of the muzzle member, whereby the seating of the abutting faces puts longitudinal strains of tension on the outer member and longitudinal strains of compression upon the inner member.
17. A gun formed of two main members, namely a body member which constitutes the main body and a portion of the chase of the gun, and a muzzle member, said members being assembled together by overlapping the rear end of the muzzle member upon the forward part of the body member for a considerable portion of the longitudinal dimension of the gun; the interior diameter of the overlapping part of the muzzle member before assembling being less than the outer diameter of the overlapped part of the body member, so that after the rear end of the muzzle part has been shrunk on the front end of the body part, the friction by the pressure between these overlapping parts will hold them firmly together; these two main parts of the gun each having been bored and rifled before assembling, and in such a way that when assembled, the bore of each part will be of uniform diameter all the way in each piece and will be of the same diameter in the overlapped part of the body as it is in the muzzle adjoining, the portion of the body which is overlapped by the muzzle part after assembling having been compressed when being bored to the same extent that it will be in the finished gun after assembling and that part of the muzzle member which overlaps the body member having been extended to the same extent while the muzzle part was being bored that it will be when the two main parts of the gun are finally assembled.
18. A gun formed of two main members, namely a body member which constitutes the main body and a portion of the chase of the gun, and a muzzle member, said members being assembled together by overlapping the rear end of the muzzle member upon the forward part of the body member for a considerable portion of the longitudinal dimension of the gun; the interior diameter of the overlapping part of the muzzle member before assembling being less than the outer diameter of the overlapped part of the body

member, so that after the rear end of the muzzle part has been shrunk on the front end of the body part, the friction by the pressure between these overlapping parts will hold them firmly together; these two main parts of the gun each having been bored and rifled before assembling, and in such a way that when assembled, the bore of each part will be of uniform diameter all the way in each piece and will be of the same diameter in the overlapped part of the body as it is in the muzzle adjoining.

19. A gun formed of two main members, namely a body member which constitutes the main body and a portion of the chase of the gun, and a muzzle member, said members being assembled together by overlapping the rear end of the muzzle member upon the forward part of the body member for a considerable portion of the longitudinal dimension of the gun; the interior diameter of the overlapping part of the muzzle member before assembling being less than the outer diameter of the overlapped part of the body member, so that after the rear end of the muzzle part has been shrunk on the front end of the body part, the friction by the pressure between these overlapping parts will hold them firmly together; these two main parts of the gun each having been bored and rifled before assembling, and in such a way that when assembled, the bore of each part will be of uniform diameter all the way in each piece and will be of the same diameter in the overlapped part of the body as it is in the muzzle adjoining.

20. A gun formed of two main members, namely a body member which constitutes the main body and a portion of the chase of the gun, and a muzzle member, said members being assembled together by overlapping the rear end of the muzzle member upon the forward part of the body member for a considerable portion of the longitudinal dimension of the gun; each member being formed in its overlapped portion with a plurality of diameters, the interior diameters of the overlapping parts of the muzzle member before assembling being less than the exterior diameters of the corresponding parts of the overlapped body part, these relative diameters of the overlapping parts causing a large tangential strain of tension in the overlapping muzzle part, and a large strain of compression in the overlapped

- body part when assembled, and one of these two main parts of the gun having been bored before assembling with the other, the overlapping part of this member having had such a tangential strain put upon it during the time of boring that the bore of this overlapped part will have the same diameter when being bored that it will have when assembled in the finished gun.
21. A gun formed of two main members, namely a body member consisting of the main body part of the gun and a portion of the chase of the gun, and a muzzle member consisting of a large portion of the chase of the gun, said members being assembled together by overlapping the rear end of the muzzle member upon the forward part of the body member for a considerable portion of the longitudinal dimension of the gun, each member being formed in its overlapped portion with a plurality of diameters, the interior diameters of the overlapping parts

of the muzzle member before assembling being less than the exterior diameters of the corresponding parts of the overlapped body part, these relative diameters of the overlapping parts causing a large tangential strain of tension in the overlapping muzzle part and a large tangential strain of compression in the overlapped body part after these two main parts have been assembled, each of these two main parts having been bored before assembling with the other, the overlapping parts of each of these main parts when being bored having had such tangential strains put upon them, that when these two main parts have been assembled with each other, the diameter of the bore, in, and near the overlapped part will be of one continuous size.

The foregoing specification signed at Glenbrook, Connecticut, this thirtieth day of August, 1916.
